CLAIM

The ornamental design for a negative pressure wound therapy tubing adapter as shown and described.

DESCRIPTION

FIG. 1 is an overhead perspective view of a negative pressure wound therapy tubing adapter of our new design; FIG. 2 is a front elevational view of the negative pressure wound therapy tubing adapter of FIG. 1; FIG. 3 is a rear elevational view of the negative pressure wound therapy tubing adapter of FIG. 1; FIG. 4 is a left-side elevational view of the negative pressure wound therapy tubing adapter of FIG. 1; FIG. 5 is a right-side elevational view of the negative pressure wound therapy tubing adapter of FIG. 1; FIG. 6 is a top plan view of the negative pressure wound therapy tubing adapter of FIG. 1; and, FIG. 7 is a bottom plan view of the negative pressure wound therapy tubing adapter of FIG. 1.

The broken lines in the drawings are included for the purpose of illustrating environmental structure and internal features that forms no part of the claimed design.
